LOOSE-LEAF BINDER

Edward C. Williams, Peterborough, Ontario,
Canada

Application March 24, 1944, Serial No. 527,911

3 Claims. (Cl. 129—24)

My invention relates to improvements in split ring loose leaf binders.

An object of my invention is to provide a split ring binder in which the rings are latched closed and so arranged that it is not liable to be inadvertently sprung open and have the contents spilled.

Another object of my invention is to provide a construction of loose leaf binder which for a given thickness of book when closed will accommodate a maximum thickness of papers in such a manner that when the book is opened the papers may be easily manipulated without danger of tearing.

Another object of my invention is to provide a split ring binder of rugged construction and one which has a minimum number of parts which are easily fabricated and lend themselves to low cost manufacture.

Other objects and advantages of my invention will become apparent from a consideration of the following detail description of a specific form of my invention in which Fig. 1 is a plan view of the assembled metal parts of my binder; Fig. 2 is an end view of Fig. 1; Fig. 3 is an end view similar to Fig. 2 but with the split rings in closed position; Fig. 4 is a cross-section on the line A—A of Fig. 1; Fig. 5 is a cross-section on the line B—B of Fig. 1; Figs. 6 and 7 are perspective views of the parts of the closing and latching mechanism on a larger scale than the preceding figures; Figs. 8 and 9 are end views of the loose leaf binder illustrating the location of the papers in the closed and in the open position, part of the binder being broken away; Fig. 10 is a view on the same scale as Fig. 1 of a metal blank from which the structure of Fig. 1 is formed.

Referring to the drawing, a pair of elongated sheet metal strips slightly concaved transversely are shown at 10 hinged together by the inter-engagement of integral lugs 11 provided on their edges, four hinges being shown. The strips 10 are retained in their assembled hinged relation against endwise movement by the detents 12 formed on their adjacent edges. Each of the strips 10 is provided with three integral ring sections 13 extending outwardly from the concave sides, the meeting ends of each pair of ring sections having interfitting parts 33. Each strip 10 is provided adjacent each end with an integral ear 14 extending outwardly on the same side as the ring sections 13. A camming lever 15 extends between and cooperates with each pair of adjacent ears 14 in such a manner that

when moved to the position shown in Figs. 1 and 2 the rings may assume their open position and when moved to the position shown in Fig. 3 the levers cam the rings closed and latch them in closed position. Cover boards 16 are attached by applying their interconnecting section 17 to the convex side of the strips 10, as by gluing. A piece of fabric glued to the inside of the cover board 16 extends over and is glued to the concave side of the strips 10.

The construction of the ears 14 and the camming lever 15 is best shown by the Figs. 6 and 7. The ear is bent back an amount somewhat greater than a right angle. The plane of the central part of the ear lies at an angle to the hinged edge of the strip, the distance between the surface of adjacent ears increasing in a direction away from the end of the strips 10 as can be seen in Figs. 2, 3, 8 and 9. Each ear is provided with a central opening 19 with a slot 20 extending radially therefrom. A depression 21 is provided on the back surface of each of the ears 14, that is the surface of the ears away from the hinged edge of the strips 10, and extends radially from the opening 19. The lever 15 best seen in Fig. 7 is a flat piece stamped from sheet metal, has a handle portion 22, a pintle 23 on each side of a width slightly less than the opening 19 in the ears, and upstanding portions 24 are provided at the outer ends of the pintles 23. The slots 20 in the ears permit the ends 24 to be passed therethrough and the lever 15 to be assembled in a pair of ears with the pintles 23 journaled in the openings 19. When so assembled and moved towards a vertical position, that is towards a position at right angles to the strips, the shoulders 25 of the ends 24 bear on the back surface of their associated ears and cam them together consequently moving the strips about their hinges 11 to close ring sections 13. The resiliency of the metal parts permits further movement of the lever until the shoulders 25 snap into the depressions 21, this latching the rings closed.

The rings 13 are elliptical in shape with the major elliptical axes perpendicular to the point of attachment to the strip. This is an important feature of my invention in that it permits a maximum thickness of sheets to be satisfactorily accommodated in a binder of given thickness. When the well known circular split rings are used, say of one and one half inches in diameter, it is found that if a thickness of more than about an inch of papers is applied to the rings that it is difficult to maneuver the papers

on the rings without binding and without tearing the paper at the perforations. In the construction of my invention using rings of greater diameter in a direction parallel to the cover boards when closed than their diameter at right angles thereto I have overcome this difficulty as will be seen from a consideration of Figs. 8 and 9. In Fig. 8 it will be observed that in the closed position the thickness of the binder is determined by the lesser diameter of the rings, the longer diameter of the rings lying parallel to the binder covers 16. I have shown the binder completely filled with papers 26, the line of the customary paper perforations being indicated at 27. When the top cover is moved to the open position as shown in Fig. 9 the rings assume a position with their long diameter at right angles to the line of the covers, and the papers move along the rings and assume the position shown occupying a portion only of the length of a ring section. The extra vertical space now available from the top of the paper sheets to the top of the rings provides a clearance whereby a sheet or sheets may be freely moved to the other side of the ring. It will be observed that while in the closed position the book may be filled to capacity and hence the space occupied in a filing cabinet occupied by the binders is used to maximum advantage, and that when in open position the clearance afforded by the elongated rings in this position overcomes the difficulty in manipulating the papers which would be the case if the rings were circular.

It will be observed that when the rings are closed the lever 15 is in a position inside the overall dimensions of the binder and are not in a position where they will be accidentally released, but they are readily accessible to engagement by the fingers for release when desired.

The construction of my invention is of few parts, four metal parts only being used and these may be made from only two different stampings. I have illustrated in Fig. 10 a stamped sheet metal blank 28 from which the metal strips 10 with their associated parts may be formed. To make one part the body of the blank 28 is pressed to be slightly concave, the portions 29 are bent back over the concave side of the strip to the positions previously described to form the ears 14. The portions 30 of the blank are formed transversely into U-shape and bent back over the concave side of the strip and formed into ring sections 13. The portion 31 projects from the same edge of the blank as the portions 29 and 30 and has an extension 32 lying parallel to and spaced from the edge of the blank. This portion 31 is bent at its line of junction with the blank toward the same side of the blank as the ears 14 and the rings 13, to a position about forty five degrees from the plane of the blank to form one half of the hinge 11. The spacing of the portions 29, 30 and 31 along the edge of the blank is so selected that another similar blank may be reversed so that the extensions 32 face in the opposite direction to that shown in Fig. 10, and the parts 29, 30 and 31 thereon are then formed in the manner above described. A pair of complementary sections 10 are thus provided from a single blank shape.

It will be observed that the ends of the portions 30 are toothed and notched, the notch shown on one side of the end being complementary to the tooth shown on the other side thereof, whereby in forming a pair of complementary sections 10 as above described the ends of the pair of rings will interfit.

To assemble the pair of complementary strips 10 the oppositely facing hinge lugs are slid together with the neck 31 of each engaging beneath the extension 32 of the other. The sections are retained in assembled relation by bending the detents 12 to a position where they block disengagement of the assembled parts both in open and closed positions of the rings but do not interfere with the hinging action thereof. A similar lever 15 may then be assembled in each pair of adjacent ears at each end by springing their end parts 24 through the slots 20 provided for that purpose.

As has been described only two different metal blanks have to be punched to provide the four metal parts which makes for economical manufacture and the economical use of metal. Also, no separate springs are required, the inherent resiliency of the bent metal parts providing the force whereby the rings are retained closed by the latching of the levers 15 in the notches 21 in the ears 14.

While in the specific example described I have shown the ring sections 13 formed integral from metal of the strips 10, with the manufacturing advantages stated it is apparent that the advantages of my invention may be retained if it is found expedient to form the ring sections 13 separately and secure them to the strips 10, in any known manner as by brazing or staking. A three ring binder has been shown but it is obvious that as many rings as required to take standard perforated sheets may be provided.

While I have described in detail a specific form of my invention it will be understood that I aim to include all such modifications and variations as fall within the scope of the appended claims.

What I claim as new and desire to secure by Letters Patent of the United States is:

1. A loose leaf binder comprising a pair of sheet metal strips hinged together at their edges, complementary ring sections rigidly connected to and upstanding from the pair of strips, an integral upstanding ear at each end of each strip provided with a circular opening, the plane of each ear adjacent the opening therein lying at an angle to the hinged edge of the strips such that the distance between the ears increases in a direction from the end of the strips, a lever having pintles journaled in the openings of the opposed ears at each end of the pair of strips, the lever having shoulders engaging the surfaces of the ears on the side thereof away from the hinged edge whereby on rotation of the levers in their journals in one direction the said shoulders by their engagement with the surfaces of opposed ears cause the strips to rotate about their hinges and move the ring sections to closed position, further rotation of the levers in the closing direction against the inherent resiliency of the ears causing latching thereof by engagement of the said shoulders in depressions in the ear surfaces.

2. A loose leaf binder comprising a pair of sheet metal strips, hingedly connected at their edges by interlocking detents thereon, integral complementary ring sections projecting from the hinged edges, integral ears bent from the strip material and extending from the hinged edges adjacent each end of each strip in the same general direction as the ring sections, a lever having pintles journaled for rotation in openings

provided in the pair of opposed ears at each end, said levers having shoulders engaging the surface of the ears remote from the hinged edge, the location of the planes of the surfaces of the ears with respect to the hinged edge being such that on rotary movement of the levers the shoulders thereon force the ears towards one another, moving the strips about their hinges and closing the rings.

3. A loose leaf binder comprising a pair of sheet metal strips transversely curved and hinged together edge to edge, a plurality of ring sections extending from the adjacent edges of

5 the strips and lying over the concave side thereof, an integral ear bent from each strip at its hinged edge near the end thereof to extend over the concave side, an operating lever at each end of the strips journaled for rotative movement in a pair of said ears, the levers and ears constructed with cooperating cam surfaces whereby on rotative movement of the levers to positions at right angles to the strips the ears are drawn towards one another and rotate the strips about the hinges and close the rings.

EDWARD C. WILLIAMS.
